UNITED STATES PATENT OFFICE.

JOHN G. ZIMMERMANN, JR., JOHN J. ZIMMERMANN, AND RIVINGTON A. STILES, OF WEST TROY, NEW YORK.

CAR-BRAKE.

SPECIFICATION forming part of Letters Patent No. 436,517, dated September 16, 1890.

Application filed July 2, 1890. Serial No. 357,541. (No model.)

To all whom it may concern:

Be it known that we, JOHN G. ZIMMERMANN, Jr., JOHN J. ZIMMERMANN, and RIVINGTON A. STILES, all of West Troy, in the county of 5 Albany and State of New York, have invented new and useful Improvements in Car-Brakes, of which the following is a specification.

Our invention relates to improvements in 10 car-brakes; and the object of our invention is to provide a simple, effective, and reliable mechanism for checking the movement of railway-cars. This object we attain by the mechanism illustrated in the accompanying 15 drawings, which are herein referred to and form part of this specification, and in which—

Figure 1 is a longitudinal section of the lower part of a street-car, on the line X X of Fig. 2. Fig. 2 is an inverted plan view of the 20 same. Fig. 3 is an inverted plan view of a modified form of our invention as adapted for applying the brakes at diametrically opposite sides of the same pair of wheels; and Fig. 4 is an inverted plan view of another 25 modified form of our invention.

As represented in the drawings, A designates the bottom of a railway-car; B, the wheels and axles for same; C, the brake-beams suspended from the bottom of the car by means 30 of links D, and E brake-shoes attached to said brake-beams and fitted to be moved into contact with the periphery of the car-wheels. All of said parts being old and of a well-known construction, constitute no part of our 35 invention.

F is a rocker-shaft journaled in hangers G, secured to the bottom of the car and provided with arms H, which are located near the opposite ends of said shaft, one of said arms projecting from the upper side of said shaft in a 40 radial line, and the other projecting in like manner from the lower side of the shaft F. Between the arms H there is a pair of eccentricities I, secured to the shaft F, and so arranged 45 that the throw of one eccentric will be in a reversed direction in respect to the other. Said eccentricities are provided with the usual eccentric hooks, and each of the latter is provided with an eccentric-rod J, which is 50 preferably provided with a right-and-left nut K, for the purpose of adjusting the length of

each of said rods with exactness. Said eccentric-rod lead in opposite directions—one leading toward the forward end of the car and the other toward the rearward end—and each 55 is connected by a joint-piece L to the particular brake-beam C to which it is appropriated. At each end of the car there is a vertical shaft M, provided with a lever, hand-wheel, or other suitable appliance for imparting a rotatory 60 motion to said shaft, and to the lower end of said shaft an arm N is secured. Each of the latter has a rod O jointed thereto, and the opposite end of said rod is jointed to the rock-shaft arm H, to which it is especially appro- 65 priated.

Our invention operates in the following manner: When the brake-shoes E are drawn back from the periphery of the wheels, as shown in Fig. 1, the brake can be applied by 70 partially rotating the shaft M at either end of the car. Thereby the rock-shaft F will receive a partial rotation, which will move the eccentricities I, so as to draw the brake-beams C toward the wheels B, thereby bringing the 75 brake-shoes E into frictional contact with the periphery of the wheels, and thereby preventing the latter from rotating. This prevention will continue during the time that the brake-shoes remain in contact with the periphery of 80 the wheels, and it can only be terminated by turning one of the shafts M in a reverse direction. In this respect our brake operates differently from those commonly used, which are provided with ratchet wheels and pawls 85 for holding the operating-shafts while the brake-shoes are in frictional contact with the wheels, and in which a release of the pawl from the teeth of the ratchet-wheel effects the removal of the brake-shoes from the 90 wheels.

In the modification of our invention shown in Fig. 3, in which the eccentric-rod J are not connected directly to the brake-beams, and which is especially designed for use on electric or other cars where it is preferred to apply the brake-shoes to opposite sides of the periphery of each wheel, a horizontal lever P is suspended from the bottom of the car over each of the axles, said lever being arranged 95 transversely to the centerline of the car. The eccentric-rod J appropriated to operating said 100

lever is connected, as at I, to one extremity of said lever, and two links Q are jointed to said lever, so as to extend laterally from opposite sides thereof. The point of connection 5 of one of said links to said lever is at the extremity that is opposite to the one to which the eccentric-rod J is connected, and the other link is connected to said lever at a point that is intermediate between the connection of 10 said eccentric-rod and the first-named link. The latter and the eccentric-rod lead from the same side of said lever, but the other link leads from the opposite side, as shown in the drawings. Two brake-beams C are employed— 15 one diametrically opposite to the other in respect to the wheels on which the brake mechanism is to operate—and each is provided with brake-shoes E. The rocker-shaft F and the appurtenances thereto belonging are substantially the same as the like parts shown in 20 Figs. 1 and 2, and they operate in a like manner. On applying a strain to the lever P by means of the eccentric connected thereto, said lever will be moved to draw the two brake-beams C toward the wheels, the pivots of the 25 links Q in said lever operating as fulcrums for said lever, and thereby the wheels will be immovably clamped between the brake-shoes E.

30 In the modification shown in Fig. 4, which is designed for use on passenger-cars and freight-cars which are provided with independent trucks at each end, the brake-shoes E are fitted to bear against the periphery of 35 the truck-wheels, a pair of said shoes bearing at one side of the periphery of one pair of the wheels of a truck, and the other pair of the shoes bearing at the opposite side of the periphery of the other wheels. In this modification the lever P is preferably fulcrumed to 40 a hanger S, secured to the bottom of the un-

der side of the car, and thereby a fixed fulcrum is obtained, so that in case the brake-shoes for one pair of the wheels become inoperative those for the other pair of wheels will be serviceable for the purpose of arresting the motion of the car; but, when preferred in this modification, the lever P may be suspended from the bottom of the car, as in the other modification; but in such cases said lever should be located intermediately between the two axles instead of directly over either. 45 What we claim as our invention, and desire to secure by Letters Patent, is—

1. In a car-brake, the combination of brake-beams provided with brake-shoes, a rocker-shaft provided with a pair of eccentrics whose centers are arranged at opposite sides of said shaft, said eccentrics being connected to said brake-beams so as to move the latter relatively in opposite directions, and mechanism whereby a rocking motion can be imparted to said shaft from opposite ends of a car, as and for the purpose herein specified. 55

2. In a car-brake, the combination of brake-beams provided with brake-shoes, a rocker-shaft provided with a pair of eccentrics whose centers are arranged at opposite sides of said shaft, horizontal levers arranged adjacently to said brake-beams and connected to said 65 eccentrics and brake-beams, so as to move the latter relatively in opposite directions, and mechanism whereby a rocking motion can be 70 imparted to said shaft from opposite ends of the car, as and for the purpose specified.

JOHN G. ZIMMERMANN, JR.
JOHN J. ZIMMERMANN.
RIVINGTON A. STILES.
